UNITED STATES PATENT OFFICE.

LEROY BAUMGARTL, OF HUBBARD WOODS, ILLINOIS, ASSIGNOR TO FEDERAL CEMENT
TILE COMPANY, OF CHICAGO, ILLINOIS, A CORPORATION OF ILLINOIS.

BUILDING SLAB.

Application filed January 12, 1925. Serial No. 1,741.

To all whom it may concern:

Be it known that I, LEROY BAUMGARTL, a citizen of the United States, residing at Hubbard Woods, 1180 Oakley Avenue, in 5 the county of Cook and State of Illinois, have invented new and useful Improvements in Building Slabs, of which the following is a full, clear, concise, and exact description, reference being had to the accompanying drawing, forming a part of this specification.

This invention relates to improvements in building slabs or tiles of concrete, clay or like substances which are used in the construction of walls, floors, ceilings, roofs, etc., and more particularly to a tile or slab of this character composed of concrete and some aggregate having spongy characteristics, whereby the finished tile or slab 15 is adapted to readily receive and positively hold nails driven into said slab and whereby the heat insulating qualities of the slab are greatly increased.

In the use of concrete slabs or tiles in the construction of roofs it frequently is desirable to cover said tile with shingles or other coatings which can only be properly secured to the tiles by nailing the shingles or covering thereon. The practice in the 20 construction of roofs of this kind has been to construct the concrete roof on the job and then pour on the completed concrete roof the desired spongy aggregate to provide the desired nailing surface. This method 25 of construction has very serious installation and maintenance disadvantages and results in a waste of material, all of which are obviated in constructing such tiles according to the teachings of this invention.

One of the objects of this invention resides, therefore, in constructing a composite tile of concrete and composite aggregate which is adapted to receive and firmly hold nails and the like and whereby a roof 30 of the character described can be constructed with the use of less concrete, whereby marked economies are effected in the handling of the parts in shipping and installation, whereby a more uniform construction throughout the entire surface of the roof is procured because of the adaptability for the required regulation in the tile construction by standardized factory methods and whereby the heat insulating 35 quality of the finished slab is much greater

than in slabs constructed solely of concrete.

For the purpose of description, a preferred form of tile is illustrated in the accompanying drawings, in which—

Figure 1 is a plan view of the tile; 60

Fig. 2 is a side elevation of the tile, and

Fig. 3 is a view in cross-section on the plane indicated by the line 3—3 in Figure 1, looking in the direction of the arrows.

As illustrated in the drawings, the tile is 65 constructed of a concrete base 4, which is preferably equipped with a steel reenforcement 5 of either steel rods or steel netting. To the upper surface of this concrete base is secured the composite aggregate 6 which 70 is utilized as the nailing surface, and which also serves to materially increase the heat insulating quality of the completed tile. In the construction of this character of tile a form or mold of the desired dimensions 75 is used, into which the ingredients used in the layers of the composite tile are poured.

The tile may be made by any one of a number of methods, but in the preferred method the composite aggregate 6 is first 80 poured, or poured and tamped, into the mold. Onto this layer of composite aggregate, preferably while its upper surface is still soft, is poured, or poured and tamped, the layer 7 of concrete, which constitutes the concrete between the layer of the composite aggregate and the steel reenforcement 5.

When this layer 7 of concrete has been 85 poured into the mold the steel reenforcement 5 is placed in position, after which the layer 8, which constitutes the lower portion of the concrete layer 4, is poured, or poured and tamped, on top of the steel reenforcement. By pouring, or pouring and tamping, 90 the concrete on the surface of the composite aggregate 6, while it is still in a soft or tacky condition, a better bond is obtained between the spongy aggregate and the concrete than would be the case if the surface of 95 the composite aggregate was permitted to harden before the concrete is poured into the mold. However, suitable tiles or slabs can be constructed by pouring the concrete 100 in the mold after the spongy aggregate 6 has hardened, but the preferred form is to pour this concrete on the soft or tacky surface of 105 the composite aggregate 6.

The method above described is the preferred method for making tiles of this char- 110

acter, because the surface 9 of the concrete layer 4 of the slab is exposed at the upper face of the mold, and, consequently, it is possible to smoothen this upper surface in 5 any of the well known methods in the prior art and thereby get a concrete surface on the slabs of the desired smoothness. Inasmuch as the tiles in the ultimate building construction are positioned on the roof with the concrete face of the tile on the interior of the building, it is obviously more desirable to have the smoothest surface on the concrete face of the tile. The surface of the composite aggregate 6 being on the exterior of the 10 roof does not require a smooth surface, and, furthermore, it is usually covered with shingles or some other roof coating which would obscure any irregularities or roughness in its surface.

15 20 Except for the fact that it has been found that it is considerably easier to obtain a smooth concrete face on these tiles by constructing the tile as above described, there is no real preference in the method described 25 over the method of constructing these tiles, in which the concrete base 4, with its reinforcement 5, is first poured, or poured and tamped, into the mold and while the upper surface of this concrete layer is still soft 30 pouring or pouring and tamping the composite aggregate layer 6 thereon. Either one of these methods, or any slight modification thereof, in which a tile having a concrete base and a composite aggregate bonded thereto in substantially the proportions to be 35 hereinafter described can be utilized, depending upon the manufacturing and installation conditions and requirements.

40 The manufacture of these slabs in the factory in forms or molds results in a uniform product and in a slab having a strength capable of resisting without breakage the necessary handling in shipping and installation. Thus, it has been found in practice 45 that composite tiles of this character can be manufactured to resist the ordinary usage in handling and installation without breakage in which the concrete base is substantially one (1) inch thick and in which the 50 spongy aggregate secured to said base is one and one-half (1½) inches thick, making an over-all thickness for the completed tile of two and one-half (2½) inches. A concrete tile one (1) inch in thickness is too fragile to 55 withstand the usual effects of handling and installation but when this one (1) inch concrete slab is fitted with the one and one-half (1½) inch coating of spongy aggregate, the strength of the completed tile is suffi- 60 ciently great so that breakage in handling and installation is not excessive. This layer of spongy aggregate also materially increases the heat insulating quality of the completed tile.

65 66 For this reason, when these tiles are con-

structed according to standardized factory methods in forms or molds provided therefor, the amount of concrete required in constructing a roof on which it is desired to place a coating of spongy aggregate for 70 nailing purposes can be very materially decreased. Likewise, it is exceedingly difficult to commercially construct a roof which has a marked pitch or inclination with a coating of this spongy aggregate, except with the 75 composite tile manufactured in accordance with the teachings of this invention.

In constructing a roof with such tiles they are placed side-by-side and are cemented together at their abutting edges by an elastic cement-filler. The composite aggregate 6 which is placed on the top of the concrete base 4 is preferably made of mineralized sawdust mixed with Portland cement and water. This composite aggregate has heat insulating qualities which are greatly superior to those of ordinary concrete and the composite tile can be used to advantage because of its increased heat insulating property, even when it is not desired to utilize the nail-retaining characteristics to the aggregate 6. Obviously, any other composite aggregate in which nails can be easily driven and which will firmly hold the nails in position, and which has the required heat insulating properties, can be substituted for the specific form just described.

The tiles constructed in accordance with the teachings of this invention should be made 100 of such a size that they can be readily handled in shipment and during installation and a convenient size has been one in which the tile is five (5) feet long by two (2) feet wide by two and one-half (2½) inches thick. The 105 size of the tile can obviously be designed to suit special requirements, but should not be made too large so as to make the handling thereof unnecessarily difficult.

From the foregoing description, it will 110 now be evident that by manufacturing a composite tile of the character described in the factory where the construction is independent of weather conditions and can be positively regulated, it is possible to obtain a 115 composite tile in which the concrete necessary to give it the desired strength can be materially reduced, and in which a completed tile of uniform construction is obtained, which reduces the necessary cost of 120 handling and installation incident to the construction of roofs in which the spongy aggregate is poured upon the concrete roof after the concrete roof has been completely installed. Moreover, the tile serves the dual function of providing the nailing surface 125 and of increasing the heat insulating quality of the completed slab.

Obviously, this invention is not limited to the specific embodiment thereof herein illustrated and described, but is capable of other 130

applications and variations, the scope of the invention being set forth in the following claims:

Having thus described my invention, what I claim is new and desire to secure by Letters Patent of the United States is:

1. A roofing tile or slab as an article of manufacture, comprising a layer of concrete and a layer of composite material adapted to receive and hold nails molded together in bonded relationship, each of said layers being of insufficient strength to alone sustain the slab and roof load when the slab is supported at its ends, the united strength of the combined bonded layers being sufficient to sustain the slab and roof load when the slab is supported at its ends and whereby a material saving in concrete is effected.

2. A roofing tile or slab as an article of manufacture, comprising a layer of concrete of prescribed dimensions to facilitate handling, shipping and installation, and of a thickness insufficient to properly sustain the roof load when the slab is supported at its ends and a layer of composite aggregate adapted to receive and firmly hold nails secured in bonded relation to said layer of concrete, the two bonded layers cooperating in said bonded relation to adequately sustain said slab and the roof load when the slab is supported at its ends whereby a material saving in concrete is effected.

In witness whereof, I have hereunto subscribed my name.

LEROY BAUMGARTL.
